GAME BOARD

Charles C. Makin, P.O. Box 1346,
Delray Beach, Fla. 33444

Filed Jan. 20, 1967, Ser. No. 5,498

Term of patent 14 years

(Cl. D34—5)

FIG. 1.

FIG. 2.

FIG. 3.

FIG. 1 is a plan view of a game board showing my new design;

FIG. 2 is an enlarged plan view of the left side of the game board of FIG. 1;

FIG. 3 is an enlarged plan view of the right side of the game board of FIG. 1.

The game board is flat and the underside is devoid of ornamentation.

I claim:

The ornamental design for a game board, as shown and described.
